DES. 2043

Stuart Gwynne, of New York, N. Y.

Letters Patent No. 2043. Dated April 11th, 1865.

Design for a Trade Mark.

The schedule referred to in these Letters Patent and making part of the same.

To all whom it may concern:

Be it known that I, Stuart Gwynne, of the City of New York, County and State of New York, have originated a new design for a trade mark of which the following is a full, clear, and exact description, reference being had to the accompanying drawing, which is part of this specification.

Within a circle of about four inches in diameter draw a heavy red line. Leave a blank space of about one sixteenth of an inch, and draw a light red line concentric with the outer circle, upon the inside of the inner circle and sweep in a line parallel thereto. Insert in large red letters, the words "Pat. Open Zinc White Metal Works," and the figures, also in red, "1865." Draw a line passing centrally through the circle. Insert in red letters on the left side of the circle the word "Grade" and on the right side the letter "A," and figure 1.

From this central line introduce a small circle having a heavy outside and a light inside red line with a small space between them; and in an arch at the top of the circle the words "Right is Bright" and in three straight lines beneath the words "Open Zinc White."

Below the center line and in red color a small circle containing

2 links surrounds a figure resembling two ovals with a star at or in the upper angle of junction of the lines of the ovals, and a triangle in the lower angle of junction of the lines of the ovals. Between the points of the centre lines of the ovals the figures "J & T" are inserted and on the right of these figures a diamond shaped figure contains the letter 'C' in a small, capital; and, on the left of the figures a diamond shaped figure is dissected by four cross lines that divide the space within the diamond into variously shaped triangles, all as shown in red lines in the drawing.

What I claim as my invention and desire to secure by Letters Patent is the Design for a Trade Mark herein set forth.

In testimony whereof I have hereunto subscribed my name J. J. H.
Hennezel

J. G. Gibbons.

Surgeon M. Morehouse.

Stuart Beaman.
